UNITED STATES PATENT OFFICE

EDWIN S. PRIDHAM, OF OAKLAND, CALIFORNIA, ASSIGNOR TO THE MAGNAVOX COMPANY, OF OAKLAND, CALIFORNIA, A CORPORATION OF ARIZONA

ELECTRODYNAMIC LOUD-SPEAKER

Application filed May 15, 1929. Serial No. 363,311.

My present invention relates to a loud speaker unit, and especially to a unit that operates on the electro-dynamic principle.

Such units are now well known. They 5 include a magnetic structure providing a dense magnetic field of substantially constant value and a conductor, capable of movement transversely of the field, which is energized with current that carries the signaling impulses. The reaction between the field and the current in the conductor causes the conductor to move in accordance with the signaling impulses, and thereby to vibrate an air actuator, such as a cone or 15 diaphragm.

These devices operate very satisfactorily when the magnetic field is obtained with the aid of an electro-magnet energized by a constant potential source of electromotive 20 force, such as a battery. If, however, it is attempted to provide a magnetic field by using a fluctuating current, such as is obtained by the rectification of an alternating current, it is found that these fluctuations 25 are apt to cause annoying extraneous sounds in the loud speaker. In late years, the desirability of operating dynamic speakers from rectified current has been recognized, especially in connection with so-called "electrically operated" radio sets. Hence, it is 30 urgent that some scheme be provided for eliminating the effects of the fluctuations.

It is, accordingly, one of the objects of my invention to make it possible, in a simple 35 and inexpensive manner, to overcome these disadvantages due to the fluctuations.

In a prior patent, Number 1,105,924, issued to me and Peter L. Jensen, as joint inventors, there is disclosed a means for neutralizing fluctuations in the electromotive 40 force used in magnetizing an electro-dynamic telephone. In this patent, however, the neutralizing coil is shown as mounted upon a separate core which is independently 45 energized by an additional electro-magnetic coil and the arrangement is such that the neutralizing coil can be moved for the purpose of varying its effectiveness. This arrangement, as will be readily appreciated, 50 is somewhat expensive and cumbersome

when embodied in present day types of apparatus and it is, therefore, a further object of my invention to provide an improved neutralizing means and arrangement of apparatus which is particularly adaptable to 55 present day devices.

My invention possesses many other advantages, and has other objects which may be made more easily apparent from a consideration of one embodiment of my invention. For this purpose I have shown an embodiment of my invention in the drawing which accompanies and forms a part of the present specification. I shall now proceed to describe this embodiment in detail, 65 as it fully illustrates the general principles of my invention.

Referring to the drawing:

The single figure is a diagrammatic view, showing my invention as applied to a loud 70 speaker, the structure of which is diagrammatically illustrated in section.

The magnetic circuit that produces the magnetic field is formed partly by a casing 10 of magnetic material. The end of the 75 casing is closed by an end member 11 having a circular aperture 12, into which projects the end of a pole piece 13, thereby forming an annular air gap between the walls of aperture 12 and the pole piece 13. 80 In the present instance, the pole piece 13 is held in the casing by a bolt 14.

The magnetic field is energized by an exciting coil 15 disposed on the pole piece 13, whereby radial lines of magnetic flux 85 are produced across the annular air gap at the end of the pole 13. The coil 15 is shown as indirectly energized from a source of alternating current, such as the primary coil 16 of a transformer. The secondary 90 coil 17 is in series with the coil 15; and a rectifier is also included in the coil circuit. Such a rectifier can be a vacuum tube device 18, or it can be of any other desired type that is capable of passing a sufficient 95 current through it to the coil 15.

The signaling impulses are impressed upon an annular voice or modulated current coil 19 disposed in the annular air gap. This coil is mechanically connected to an 100

air actuator, as for example, to the small end of a light, rigid cone 20, the edge of which is appropriately supported.

It is evident that, without further apparatus, the coil 19 will be axially urged with a force depending on the current flowing in the coil 19, and on the intensity of the magnetic field in the annular gap. If this intensity varies due to the current fluctuations in coil 15, then a movement is imparted to coil 19 that is superposed upon the movement due to the signaling impulses.

In order to neutralize the effect of these fluctuations, I provide a fixed or stationary coil 21 that is disposed on pole piece 13 adjacent the annular gap, and in series with the voice coil 19. This coil 21 is wound with rather large wire to keep its resistance low. It is held in place against a shoulder 22 on the pole piece 13 formed by upsetting the material. The shoulder 22 also serves to hold the coil 15 in place.

Since the function of the coil 21 is to neutralize the effect of field current variations on the voice or diaphragm actuating coil 19 it must be located at a point where it will be in inductive relation with the field coil 15. The coil 21 is therefore preferably located upon the central pole piece 13 in close coupled relation with the magnetic field energizing coil 15. When the neutralizing coil 21 is thus mounted in closed coupled relation with the field coil 15 it will, due to magnetic leakage and the disposition of the voice coil 19 in the air gap, be encircled by more of the total flux of the magnetic field than will be the voice coil 19 and consequently it may be said to be more sensitive to field current changes than the voice coil.

As a result of the above suggested difference in sensitivity the neutralizing coil 21 is generally provided with a fewer number of turns than the voice or diaphragm coil 15. When the proper number of turns is provided in the neutralizing coil 21 it is possible to completely eliminate all hum in the apparatus due to variations in the exciting current flowing through the field coil 15 and at the same time not interfere with the free movement of the diaphragm actuating coil 19 in response to the modulated signal current impressed thereupon.

If we assume that a fluctuation produces a current in the coil 15, this fluctuation will also induce an electromotive force in the neutralizing coil 21; and when this coil 21 is connected in series circuit and opposed to the voice coil 19, the E. M. F. induced therein will oppose the electromotive force induced in the coil 19 due to this fluctuation. From this, it will be seen that by a proper choice of relative number of turns in coils 19 and 21, these opposing effects can be fairly well balanced, so that the ultimate result will be a substantial neutralization of

the disturbing effects due to variations in the rectified current for the complete range of operation.

Recapitulating, when the neutralizing coil 21 is connected in series with the moving or voice coil 19 and the secondary 17 of the coupling transformer, as illustrated, the neutralizing coil being wound about the pole piece 13 of the electro-magnet, it will be seen, since the rectifier 18 supplies to the electro-magnet coil 15 a pulsating current, that the magnetic flux produced by the coil 15 will also fluctuate. Since the moving coil is in the field of this flux, there will be a reaction between it and the magnetic flux and, as a result, the voice coil 19 will tend to move, its movements having the same frequency as the fluctuations in the field current. If the diaphragm moves, however, sound will be produced and, as a result, we would get an audible hum. With my invention, the effect of the pulsating field current is, however, nullified or neutralized by the neutralizing coil 21, which coil is also in the magnetic field produced by the coil 13, and it, therefore, has induced in it a voltage corresponding in frequency to the pulsating magnetic field energizing current. The voltage thus induced in the neutralizing coil will send a current around the circuit consisting of the transformer, the moving voice coil, and the neutralizing coil. With this arrangement, the magnitude of this induced current will be such that its effect on the moving voice coil will be equal and opposite to that produced directly on the moving coil by the flux of the magnetic field, and since the two effects are equal and opposite, they will neutralize each other and prevent the diaphragm 20 from being actuated due to variations in the energizing electromotive force and thus producing a hum corresponding thereto.

While I have shown the preferred form of my invention as now known to me, it is to be understood that various changes may be made in its construction without departing from the spirit of the invention as defined in the appended claims.

Having thus described my invention, what I claim and desire to secure by Letters Patent is—

1. In a signal reproducer, means for electro-magnetically producing a magnetic field, a diaphragm, a conductor for actuating said diaphragm capable of being energized from an external source of modulated current and moving transversely to said field, and a second stationary conductor connected in series circuit with said first conductor and disposed in inductive relation with respect to said electromagnetic field for neutralizing currents induced in said conductor by variations in the strength of said magnetic field.
2. In a signal reproducer, a magnetic field

- structure having an air gap, a coil for magnetizing said magnetic field structure, a diaphragm, a voice current carrying conductor capable of moving transversely to the 5 magnetic field in the air gap and actuating said diaphragm, and a stationary coil connected in opposed series circuit with said voice current conductor and inductively related to said magnetic circuit for neutralizing currents induced in said conductor by 10 variations in the strength of said magnetic circuit.
3. In a signal reproducer, a magnet structure having a pole piece and an air gap between the pole piece and the rest of the 15 structure, a diaphragm actuating conductor having connections with a source of modulated current of sound producing frequency capable of transverse movement in said air gap, a coil for energizing the magnet structure to provide a magnetic flux across the air gap, and a stationary coil connected in series circuit with said conductor and with said source of modulated current disposed 20 upon the pole piece near the air gap in inductive relation with the coil which energizes the magnet structure.
4. In a signal reproducer, a magnetic structure, a pole piece in said structure and forming therewith an air gap, a coil on said pole piece for magnetizing the air gap, a diaphragm actuating conductor adapted to be energized by a modulated current of sound producing frequency and move transversely in said air gap, and a stationary coil in series circuit with said diaphragm actuating conductor and disposed on the pole piece adjacent the air gap, said stationary coil being in inductive relation with the coil that 35 magnetizes the air gap.
5. In a loud speaker of the electro-dynamic type, the combination of a magnetic field structure having an outer metallic casting and a centrally disposed core mounted 40 therein, a winding upon said core for energizing said magnetic field structure, an annular pole piece for closing said magnetic field structure and forming an annular air gap at the end of said core, a voice current 45 carrying coil disposed in said annular air gap adapted to move therein and actuate a sound reproducing diaphragm, and a second coil mounted upon said core connected in series with said voice current carrying coil 50 for neutralizing currents induced in said voice coil by reason of fluctuations in the current flowing in said magnetic field energizing coil.
6. In a loud speaker of the electro-dynamic type, the combination of a magnetic field structure having an outer metallic casting and a centrally disposed core mounted 55 therein, a primary winding upon said core for energizing said magnetic field structure 60 adapted to be excited by a rectified alternat-
- ing current, an annular pole piece for closing said magnetic field structure and forming an annular air gap at the end of said core, a coil disposed in said annular air gap adapted to be energized from an external source by a modulated voice current and 65 actuate a sound reproducing diaphragm, and a secondary winding mounted upon said core adjacent said primary winding connected in series with said diaphragm actuating coil for neutralizing currents induced in said diaphragm actuating coil by reason of fluctuations in the current flowing in said primary winding.
7. In a loud speaker of the electro-dynamic type, the combination of a magnetic field structure having a centrally disposed core mounted therein, a winding upon said core for energizing said magnetic field structure, an annular pole piece associated with 80 said magnetic field structure and forming an annular air gap at the end of said core, a voice current carrying coil disposed in said annular air gap adapted to move therein and actuate a sound reproducing diaphragm, and a second and stationary coil mounted upon 85 said core connected in opposed series relation with said moving diaphragm actuating coil for neutralizing currents induced in said diaphragm actuating coil by reason of fluctuations in the current flowing in said magnetic field energizing coil.
8. In a signal reproducer the combination of a magnetic field structure, a diaphragm actuating coil having connections 90 with an external source of modulated current of sound producing frequency disposed in operative relation with said field structure, and a stationary coil disposed in inductive relation with said field structure and 95 connected to impress an electromotive force upon said diaphragm actuating coil equal and opposite to the electromotive force generated in said latter coil by variations in the flux of said magnetic field.
9. In a sound reproducing system, the combination of a field structure having an air-gap, a field coil upon said field structure for producing a magnetic flux across said air-gap, a source of rectified alternating current for energizing said field coil, a modulated current carrying coil disposed in said air-gap adapted to actuate a diaphragm to produce sound, a source of modulated current for said last coil, and a neutralizing coil 100 disposed in inductive relation with said field coil and connected in series circuit with said modulated current carrying coil for preventing the reproduction of sound due to fluctuations in the rectified current which 105 energizes said field coil.
10. In a loud speaker apparatus, a magnetic circuit providing an air gap, a modulated current coil extending into the air gap and movable therein, and a fixed neutraliz-

ing coil conductively connected to the modulated current coil and disposed in inductive relation with the magnetic circuit to neutralize the effect of induced currents in the modulated current coil.

11. In a loud speaker apparatus, a magnetic circuit having an air gap, a sound producing member, a modulated current coil carried by said member and extending into the air gap, and a stationary coil associated with the magnetic circuit for generating a neutralizing current for the modulated current coil equal and opposite to the induced current in the modulated current coil resulting from flux variations in the magnetic circuit.

12. In a loud speaker apparatus, a magnetic circuit, means for energizing the magnetic circuit, a sound producing member, a modulated current coil carried by the sound producing member, and a fixed neutralizing coil associated with the means for energizing the magnetic circuit for generating a current for neutralizing currents induced in the modulated current coil.

13. In a loud speaker apparatus, a magnetic circuit comprising a cup-shaped member, a central pole piece mounted therein, an annular pole piece secured to the cup-shaped member and forming an air gap with the central pole piece, a diaphragm for reproducing sounds, a modulated current coil carried thereby and extending into the air gap, and a neutralizing coil wound upon the central pole piece for generating a neutralizing current for the modulated current coil to prevent movement of the diaphragm due to flux changes in the air gap.

14. In a loud speaker apparatus, a magnetic circuit providing an air gap, a modulated current coil extending into the air gap, a stationary neutralizing coil in series with the modulated current coil connected thereto in such a direction that the current generated in the neutralizing coil and flowing through the modulated current coil is opposite in direction to induced currents in the modulated current coil caused by flux variations in the magnetic circuit.

15. In a loud speaker apparatus, a magnetic circuit having an air gap, a field coil for energizing said circuit, an alternating current rectifier for energizing the field coil, a diaphragm for reproducing sounds, a cylinder carried by said diaphragm having a portion extending into the air gap, a modulated current coil carried by the cylinder and extending into the air gap, a neutralizing coil wound upon the central pole piece, and means for interconnecting the neutralizing coil and the modulated current coil, whereby a current is caused to flow in the modulated current coil which is equal and opposite to the current induced in the modulated

current coil by variations in the flux of the magnetic circuit.

16. In a loud speaker apparatus, a magnetic circuit having an air gap, means for supplying an energizing current therefor, a modulated current coil disposed in said air gap, and means for eliminating the effect of variations of the energizing current upon said modulated current coil comprising a stationary neutralizing coil inductively related to the magnetic circuit and differentially connected to said modulated current coil.

17. In a loud speaker apparatus, a magnetic circuit, means for energizing the magnetic circuit, a sound producing member, a modulated current coil carried by the sound producing member, and a neutralizing coil differentially connected in series with the modulated current coil and more subject to flux variations in the magnetic circuit than the modulated current coil and associated with the magnetic circuit for generating a neutralizing current for the modulated current coil.

18. In a loud speaker apparatus, a magnetic circuit, means for supplying an energizing current therefor, a voice current coil disposed in operative relation with said magnetic circuit, and means for eliminating the effect of variations of the energizing current comprising a neutralizing coil differentially connected to said voice current coil, said neutralizing coil being more subject to change of flux in the magnetic circuit than the voice current coil.
